EAR PROTECTOR

Clara Boyer, Chicago, Ill.

Application August 4, 1939, Serial No. 288,271

2 Claims. (Cl. 132—45)

This invention relates to ear protectors particularly adapted for protecting the ears against the heat of driers, such as are used for drying the hair after it has been shampooed and dressed 5 or "set."

Ear covers made of paper have been used for this purpose, but paper becomes very hot after having been subjected to the drier heat for a short time, and the construction of these articles 10 has been such that the ears could not be protected entirely, resulting in great discomfort to the user.

The main object of my invention is to provide protectors which will cover and fit the ears, 15 which will provide an air space between the protector and the outer side of the ear, and which will be comfortable and efficient for its intended purposes.

Another object is to produce a protector for 20 the purpose stated, comprising one integral piece of material, preferably felt or the like, which I have found to be well suited for protecting the wearer against heat.

Another object is to produce a protector shaped 25 so that it may be applied by being slipped over the ear from the rear, to cover the inner and outer surfaces of the ear.

In the drawing:

Fig. 1 is a front elevational view of an ear protector embodying my invention, intended for the right ear of a wearer.

Fig. 2 is an elevational view of the reverse side of the protector of Fig. 1.

Fig. 3 is a transverse sectional view taken in 35 the plane of the line 3—3 of Fig. 1.

Fig. 4 is a plan view of the single piece of material from which the protector is produced.

Fig. 5 is a vertical sectional view, taken in the plane of the line 5—5 of Fig. 4.

40 In that embodiment of the invention shown in the drawing, 10 indicates a piece of material, preferably felt or the like, having a straight edge 11 at one side, and an edge 12 inclined downwardly slightly from the upper end of the edge 11.

45 The lower portion of the edge 11 defines one side of a tongue 13 having an edge 14 downwardly inclined to a greater degree than the edge 12. Between the edge 12 and said tongue 13, the piece of material 10 is cut to form a plurality 50 of tongues, preferably six, having side edges diverging inwardly and cut off straight at their ends. The tongues are indicated at 15 to 20, inclusive, and they are non-uniform as to size

and shape, being substantially as shown in the drawing, forming spaced apart V-shaped notches in the peripheral portion of the piece 10.

The piece of material 10 is shaped as shown in Fig. 5, so as to be concave on the surface 21 5 which is toward the inside of the finished protector.

The proximate edges of adjacent tongues are stitched together by stitches 22, arranged to form seams smooth on both sides of the protector. 10 To connect the edges of said tongues, as stated, necessitates folding the material so that the tongues extend inwardly and lie adjacent but spaced from the concave surface 21 of the protector. 15

The finished product provides a smooth cover for the ear, in which that portion which is free from seams overlies the outwardly facing surfaces of the ear and the connected tongue portion covers the oppositely facing surfaces of the 20 ear, the end edges of the tongues fitting around the junction of the ear and head. The concave form of the blank provides ample space between the two portions of the protector to receive the ear without engaging its surfaces closely. This 25 adds to the comfort of the wearer and enhances the protection against heat rendered by the device.

Changes may be made in details of construction without departing from the scope of my 30 invention.

I claim:

1. An ear covering device consisting essentially of a single piece of material having a smooth unseamed portion adapted to overlie the outwardly facing surfaces of the ear, and having a series of tongues integral with said unseamed portion, said tongues being stitched together and forming a portion of the device for covering the oppositely facing portion of the ear, said piece 35 of material being concavo-convex, and the concave side being on the inside of the finished device.

2. An ear covering device consisting essentially of a single piece of heat resisting material having a portion adapted to cover the outwardly 45 facing surfaces of the ear, and having a series of spaced apart tongues initially extending outwardly from said portion, the tongues being folded inwardly and stitched together and adapted to cover the oppositely facing surfaces 50 of the ear.

CLARA BOYER.
